UNITED STATES PATENT OFFICE.

CARL SCHAUM, OF PHILADELPHIA, PENNSYLVANIA, ASSIGNOR TO FLETCHER WORKS, INCORPORATED, OF PHILADELPHIA, PENNSYLVANIA, A CORPORATION OF PENNSYLVANIA.

CENTRIFUGAL.

Application filed January 15, 1927. Serial No. 161,391.

My invention relates to an improvement in centrifugals or extractors, and has for one of its objects the provision in such a device of an improved construction whereby the operation and servicing of the same are improved.

A further object of my invention is the provision of an extractor or centrifugal which is steam-driven, means being provided, however, whereby the entry of steam to the basket of the centrifugal is prevented, thereby preventing injury to the contents thereof.

A still further object of my invention is the provision of a centrifugal wherein the tub is divided into upper and lower compartments out of communication with each other at all times, which permits of a steam drive for the basket which is mounted within one of these compartments without the entry of steam into the basket.

Another object of my invention is the provision of a centrifugal which is under-supported but which does not require the pit customarily employed.

In general, my invention provides a centrifugal comprising a stationary tub provided with upper and lower compartments out of communication with each other. In the upper compartment of the tub I provide an extractor basket which is supported on and attached to a rotatable shaft extending vertically of the tub. A portion of this shaft extends into the lower compartment of the tub, and has attached to it a series of turbine blades to which steam is admitted to drive the basket.

This provides an exceedingly compact and efficient machine in which steam may be employed as the motive fluid without danger of injury to the contents of the extractor basket.

In the accompanying drawings I have shown two embodiments of my invention, Fig. 1 illustrating one embodiment in part sectional elevation;

Fig. 2 being a section on the line 2—2 of Fig. 1, and

Fig. 3 illustrating a modification.

Referring to the drawings in detail, and first of all to Figs. 1 and 2, 1 designates an extractor tub constructed so as to provide two compartments, an upper compartment 2 and a lower compartment 3. These two compartments are maintained out of communica-

tion with each other at all times by a wall or partition 4. This partition is shaped so as to provide a hub or bearing 5. This bearing or hub is stationary and extends vertically of the tub.

In the upper compartment 2 of the tub I provide a rotatable centrifugal basket 6, provided with a brake B for bringing the tub to rest, and with a vertically-extending centrally-located portion 7, which provides a hub 60 adapted to telescope and to rotate about the hub 5 of the centrifugal tub.

The centrifugal is provided with a supporting shaft 8 extending vertically of the machine and passing through the hub 7 of the basket and the hub or bearing 5 of the tub. At the upper end of this shaft is a governor comprising governor arms 9, governor spring 10, and a cap 11, the latter receiving a regulating rod 12 extending from top to bottom of the shaft 8 and projecting from the lower end of the shaft as indicated at 13. The rod 12, where it passes through the cap 11, is screw-threaded so as to be adjusted longitudinally whereby the governor 70 75 action as a whole may be regulated.

On the lower end of the supporting shaft 8 is a rotor 14 carrying turbine blades 15. The rotor is keyed to the shaft 8, as indicated at 16. The shaft 8 is also keyed to the hub 7 of the basket, as indicated at 17.

The hub or dome 7 of the basket 6 is provided with a cover 18 so that the entire mechanism so far described is wholly enclosed and so that the supporting shaft 8 90 may be said to lie wholly within the tub 1.

Steam is admitted to the turbine blades 15 through a pipe 19 and port 20, and the entry of steam to the machine is controlled by a valve 21. The stem of this valve is engaged 95 by a lever 22 which is in the form of a bell crank lever and the long arm of which is adapted to be actuated to close the valve by means of a spring 23. The action of this spring in a direction to close the valve 21 is controlled by the governor already mentioned or, to be exact, by the governor rod 18.

The entire machine is supported on hangers which may be of usual construction for the support of centrifugals, one of these hangers having been illustrated at 24.

When steam is admitted to the vanes of the turbine through the pipe 19 past the valve 21, it will be apparent that the rotor 110

14 will be rotated, and inasmuch as this rotor is keyed to the supporting shaft 8, the shaft and centrifugal basket will be caused to rotate. The speed of rotation of the turbine rotor is, of course, controlled by the governor, the governor arms gradually raising the rod 13 to permit the spring 23 to close or to move the valve 21 toward closed position.

- 10 It will be apparent from the foregoing that the construction above described provides a centrifugal which is extremely simple in construction, which is wholly enclosed, and inasmuch as the two compartments or chambers 15 2 and 3 of the tub are separated from each other by the partition 4, the steam admitted to the lower compartment 3 cannot reach the interior of the basket, thereby preserving the basket, or rather the contents thereof, against 20 injury from the steam.

In the embodiment of my invention just described, the supporting shaft 8 is rotary but in the form of my invention illustrated in Fig. 3, the supporting shaft, which in this 25 instance is designated 8', is stationary. In this embodiment of my invention the basket 6' is rotatable on ball bearings 25 about the stationary supporting shaft 8'. The rotor 14' is rigidly secured to the basket 6' as indicated at 26. Turbine vanes or blades 15' are rigid with respect to the basket and rotor. The intake steam nozzle is designated 19' and it will be seen that this is set into the 30 stationary supporting shaft 8' and communicates with a port 27 extending vertically of this shaft, the steam traversing this port and entering a stationary nozzle 28 interposed in the space between the bottom of the basket 6' and the rotor 14', through which it passes to 35 impinge on the vanes 15'. This will cause the rotor 14' together with the basket 6' to be rotated. The entry of steam to the nozzle 28 is controlled by a valve 21' which in turn is controlled by a governor spindle or rod 40 13'. The steam exhausts through exhaust port 29. In this arrangement, therefore, I have provided an apparatus in which the cen-

trifugal basket is steam driven and in which steam is prevented from entering the basket owing to the fact that the rotor 14' and the 50 bottom of the basket 6' are imperforate. It will be seen also that the supporting shaft 8' in this embodiment of my invention is stationary as distinguished from the rotary shaft of Fig. 1. 55

It is to be understood that changes may be made in the details of construction and arrangement of parts herein described within the purview of my invention.

What I claim is:

1. A centrifugal comprising a stationary tub providing upper and lower non-communicating chambers or compartments, a shaft lying wholly within the confines of said tub, a portion of the shaft lying within the upper and the remainder within the lower of said chambers, a rotatable basket in the upper of said chambers and attached to said shaft, turbine blades in the lower compartment or chamber of the tub carried by said shaft to 70 drive the shaft and thereby to rotate said basket, a steam valve in the lower chamber for controlling the admission of steam to said blades, and a governor in the upper chamber controlling said valve. 75

2. A centrifugal comprising a stationary tub comprising upper and lower compartments, a rotatable basket in the upper of said compartments, a rotatable shaft lying wholly within the tub, a portion thereof lying in the upper compartment, the remainder in the lower compartment, means for affixing the shaft to said basket, turbine blades in the lower compartment attached to said shaft, the lower part of said tub being provided with inlet and exhaust ports for the entrance and exhaust of steam to and from the lower compartment of the tub to drive said shaft and thereby to drive said basket, and valve mechanism controlled from the upper of said compartments for controlling said inlet port. 80 85 90

This specification signed this 10th day of January, 1927.

CARL SCHAUM.
